UNITED STATES PATENT OFFICE.

HENRY E. PHELPS, BERNARD T. KIRK, AND JOSEPH COMSTOCK, OF RIFLE, COLORADO.

SPRING-MOTOR.

1,286,090.

Specification of Letters Patent.

Patented Nov. 26, 1918.

Original application filed November 11, 1915, Serial No. 60,927. (Patent No. 1,239,037, dated September 4, 1917.) Divided and this application filed November 7, 1917. Serial No. 200,753.

To all whom it may concern:

Be it known that we, HENRY E. PHELPS, BERNARD T. KIRK, and JOSEPH COMSTOCK, citizens of the United States of America, residing at Rifle, in the county of Garfield and State of Colorado, have invented certain new and useful Improvements in Spring-Motors, of which the following is a specification, reference being had therein to the accompanying drawing.

This invention relates to a spring motor and has special reference to divisional subject-matter contained in our prior application, Serial Number 60,927, filed November 11, 1915, and which is now U. S. Patent 1,239,037, issued Sept. 4, 1917.

One object of this invention is the production of a spring motor which is so constructed as to intermittently rotate a shaft connected thereto.

Another object of this invention is the production of a spring motor wherein a check mechanism is employed for holding the operating mechanism of the shaft for predetermined intervals whereby as the check mechanism releases the operating mechanism, the shaft will be rotated.

With these and other objects in view this invention consists in general of certain novel combinations, constructions and arrangements of parts as will be hereinafter fully described and claimed.

In the drawing:

Figure 1 is a side elevation of the spring motor.

Fig. 2 is a top plan view of the spring motor, the casing being removed.

Fig. 3 is a side elevation of a portion of the spring motor.

Fig. 4 is a side elevation of the check wheel.

Fig. 5 is a detail perspective view of the check lever.

Referring to the accompanying drawings by numerals, it will be seen that the frame comprises an inner side section 1 and an outer side section 2. These side sections 1 and 2 are held in spaced relation by means of the straps 3 which have feet 4 extending from their inner ends so as to permit the frame to be carried upon the casing 5 which, of course, may be of any suitable construction.

A shaft 6 is carried by the frame and is

intended to carry a disk or any other operating device 7 desired upon its outer end, as shown in Fig. 2. This shaft 6 is provided with a collar 8 bearing against the inner side section 1, as shown in Fig. 2, while adjacent its opposite end it carries a pinion 9 shrunk thereon or otherwise secured thereto, and on shaft 6 there is carried a ratchet 10. The spring 11 is carried upon the frame 1 and is retained in a set position by any suitable retaining means. 55 This spring 11 is wound by means of the key 12. The gear 13 of this spring 11 meshes with the pinion 14 of the gear 15 and this gear 15 in turn meshes with the gear 9 carried upon the shaft 6. Therefore, it is obvious that the tension of the spring 11 will cause rotary motion to be imparted through the pinion 14 and the gears 15 and 9 to the shaft 6 when these gears are released. 70

In order to check the operation of the spring 11, however, there is provided a pinion 16 carried upon the shaft 17 mounted upon the sections 1 and 2, and this shaft 17 is also provided with a gear 18. The U-shaped pawl 19 is secured by means of the rivet 20 to the rotatable shaft 21 also carried by the frame. This pawl 19 engages the gear 18 and, therefore, holds the gear against rotation, thus holding the spring 11 from operating until the pawl 19 releases the gear 18. In order to hold the pawl 19 in such engagement with the gear 18 so as to prevent the same from continuously rotating, there is provided a strand 22 having an offset end 23, and this strand 22 is carried by the rotatable shaft 21, as shown in Fig. 2. The manner in which this strand 22 is held in a releasable set position will be hereinafter set forth. 85

It will also be noted that the outer section 2 of the frame is provided with a strap 24 carried thereon and spaced therefrom, as shown in Figs. 1 and 2, so as to permit the lever 25 to be pivotally mounted thereon. This lever 25 is provided with a pawl 26 which engages the ratchet 10, and this ratchet 10 is provided with spaced teeth as shown clearly in Fig. 1. A coil spring 27 is connected to the forward end of this lever 25 and is also connected to the shaft of the spring 11. As a consequence, the pawl 26 is normally held in engagement with the gear 100 105

10. This lever 25 is also provided with a lug 28 formed thereon for purposes to be hereinafter set forth.

Adjacent the opposite end of the frame 5 there is carried a shaft 29 having a spring 30 keyed thereto in any suitable manner, this spring 30 being wound by the key 31 carried upon the outer end of the shaft 29. This spring 30 has the large gear 32 fastened thereto; gear 32 meshes with the pinion 33. The gear 34 meshes with the pinion 35. The gear 36 is also connected in any suitable manner to the pinion 35 while the dog 37 is pivotally mounted upon the shaft 15 38 carried upon the upper portions of the frame. The counter-balancing strand 39 is connected to the dog 37, as shown in Figs. 1 and 2, so that the counterbalancing strand will cause the dog 37 to swing back and forth, thus permitting the gear 36 to rotate with a checked action, thus permitting the gear 34 to impart a rotary motion to the gear 40 carried upon the shaft 41. This shaft 41 has a cam 42 keyed upon its outer 25 end so that as the shaft 41 is rotated the cam will come into engagement with the lugs 29 of the lever 25 for swinging the pawl 26 and this lever from engagement with the ratchet 10 at intermittent intervals. Adjacent the 30 opposite end of this shaft 41 there is also keyed the check wheel 43 which has a notch 44 formed in its periphery, as shown in Fig. 4. As a consequence, as the pawl 42 is rotated it will also be seen that the check 35 wheel 43 is rotated and simultaneously with the engagement of the cam 42 and the lug 28 of the movement of the lever, the notch 44 and the check wheel 43 will move into alignment with the offset end 23 of the check 40 strand 22, thus allowing this offset end to pass into the notch 44 for permitting the pawl 19 to release for an interval the checking action it has previously had with the gear 18. By releasing the gear 18, it will be 45 seen that the tension of the spring 11 will cause rotary motion to be imparted to the shaft 6, although after a short portion of the revolution of the shaft 6 the movement

thereof will be checked by the cam 42 releasing the lever 25, thus permitting the pawl 50 of the lever to engage one of the teeth of the ratchet 10 for checking the action of the shaft independent of the checking action imparted by the pawl 19 upon the gear 18. It is obvious that as the check wheel 43 continues to rotate, the offset end 23 of the check strand 22 will move out of the notch 44, thus moving the pawl 19 into checking engagement with the gear 18.

From the foregoing description it will be 60 seen that at intermittent intervals the lever and checking strand will be operated so as to release their checking action upon the tension of the spring 11, thus permitting the shaft 6 to rotate for a predetermined interval after which the checking action is again assumed, thus causing the shaft to be again held for a predetermined interval without moving.

What is claimed is:—

In a device of the class described, the combination with a supporting frame, driving means carried by said frame, of a shaft carried upon said frame, a gear carried by said shaft and driven by said driving means 75 whereby said shaft will be actuated, a checking wheel carried upon said shaft and having a notch in its periphery, a pawl pivotally mounted upon said frame and engaging said driving means, a checking strand connected to said pawl, said checking strand having an offset end bearing upon the periphery of said checking wheel whereby said checking strand will hold said pawl in engagement with said driving means against 80 movement at predetermined intervals, said checking wheel being moved by the action of said driving means whereby as said offset end moves into said notch said pawl will release the driving means for permitting said 85 shaft to be rotated.

In testimony whereof we hereunto affix our signatures.

HENRY E. PHELPS.
BERNARD T. KIRK.
JOSEPH COMSTOCK.
